STARTING INTERNAL-COMBUSTION ENGINES.

1,241,115.

Specification of Letters Patent. Patented Sept. 25, 1917.

Application filed June 12, 1915. Serial No. 33,726.

To all whom it may concern:

Be it known that we, OTTO HEINS, a subject of the Emperor of Germany, residing at No. 336 West 88th street, in the city, county, and State of New York, and CHARLES M. WILD, a subject of the Emperor of Germany, residing at No. 14 Springfield street, Springfield, county of Hampden, State of Massachusetts, have invented certain new and useful Improvements in Starting Internal-Combustion Engines; and we do hereby declare the following to be a full, clear, and exact description of the invention, such as will enable others skilled in the art 15 to which it appertains to make and use the same.

In starting internal combustion engines from rest, it is preferable to give the crank shaft of the engine a quick turn, rather than a lower acceleration for a longer period, because the total energy required to reliably start into action the carburetor and the ignition system if it embodies a magneto, and to cause the engine to pick up, is less, the time of starting is less, and usually the engine starts at a lower speed, which further reduces the time and energy required. The difference is particularly important when an electric motor is used for starting, inasmuch as the size of the starting battery is directly affected and also the space and weight requirements of the entire starting equipment. In using an electric motor of the series type, which is well adapted for the purpose on account of its high starting torque and its speed-torque characteristic, difficulty sometimes arises when a quick turn is produced like the rapid half or quarter turn of the crank when starting by hand, because, if the acceleration of the engine from rest is designed to be high, then the speed to which the engine is brought at this acceleration may be below the speed at which the engine starts into action under its own power, which speed is herein termed the "critical speed." This is particularly true when the engine is cold or when unusual high starting resistance in the engine must be overcome, as, for instance, on account of "frozen" bearings or insufficiently lubricated pistons. In order that the motor may reliably start the engine at all times, it has been customary to install a starting equipment designed to overcome the start-

ing resistance and bring the engine to a speed ample under the worst conditions likely to be present, which speed is herein termed the abnormal critical speed. This speed is higher than necessary for normal conditions, and it follows that the average acceleration of the engine to its critical speed is lower than would otherwise be attained with the same starting motor.

In order to keep the starting equipment small and light, advantage has been taken of the fact that the starting period is of very short duration. Thus, it is usual practice to work the motor at very high output, even up to the point of maximum output which it is capable of developing. By making the point of maximum output occur at the normal critical speed of the engine, the average acceleration of the engine up to that speed is substantially a maximum, but if, on account of abnormal conditions, the engine does not pick up at this point, the acceleration falls off rapidly thereafter, first on account of the increasing speed and secondly on account of the decreasing output, the rate of decrease depending upon the characteristics of the motor. On the other hand, if the maximum output of the motor occurs at the speed at which the engine picks up under the worst conditions of operation, then the average acceleration to the normal critical speed at which the engine starts into action under normal conditions is considerably lower than before.

We have discovered that a series motor may be worked at a higher average output than it is at present required to do in starting an internal combustion engine from rest without heating the motor to a dangerous temperature, and we have taken advantage of this condition in providing a method of starting wherein the motor will reliably start the engine under all likely conditions in a minimum time, that is, at a maximum average acceleration, and with decreased consumption of energy. In doing this, the equipment is preferably operated in such manner that the motor attains its maximum output at about the normal critical speed of the engine, but instead of allowing the output of the motor to decrease in case a higher speed should be necessary, the speed-torque characteristic developed by the motor at the engine shaft, and preferably at the shaft of

the motor itself, is changed in such manner as to cause the motor to tend to develop another point of maximum output at a higher speed. If desired, the speed-torque characteristic may be changed in this way more than once, and in fact the change from one speed-torque characteristic to another may be made gradually so that the average output of the motor in this period is thereby a maximum. Although we prefer to have the point of first maximum output of the motor coincide substantially with the normal critical speed of the engine, yet it is possible within our method of starting to have the maximum output occur before this point and thereby further increase the average acceleration and decrease the time of starting and the energy consumption to the extremity that is possible within safe heating limitations of the motor.

There are various ways in which the speed-torque characteristic developed by a series electric motor at the engine shaft may be appropriately changed during the starting period. For instance, the speed-torque characteristic of the motor itself may be appropriately changed by decreasing the excitation of the field windings of the motor, or by shunting the field windings, or by series-parallel grouping thereof, and this action may be repeated, if desired, or it may be accomplished gradually over a range of speed. A similar effect may be produced by suitably altering the ampere-turns of the armature or by cutting out some of the coils thereon, or by shunting the armature. Furthermore, the speed-torque characteristic developed by the motor at the engine shaft may be appropriately changed by changing speed gearing between the motor and the engine as described and claimed in our pending application Serial Number 33727, filed concurrently herewith. In all cases the starting equipment is designed to produce a high average acceleration from rest to normal critical speed of the engine, preferably by adapting the motor to reach the first point of maximum output substantially at the time the engine reaches its normal critical speed. If the engine does not pick up at that time, its speed may be further increased at a rate which, though less than before, is higher than the rate which would occur if the motor were allowed to continue its operation after attaining the first point of maximum output without the change introduced in accordance with our method of starting.

In the accompanying diagrammatic drawings illustrating several arrangements suitable for carrying out our invention,

Figure 1 shows an arrangement whereby the field excitation of the motor may be decreased by substituting other field coils of less ampere turns;

Fig. 2 shows an arrangement whereby the field coils may be changed from series to parallel connection with each other;

Fig. 3 shows means for shunting the field coils;

Fig. 4 shows an arrangement whereby the armature of the motor may be shunted;

Fig. 5 shows an arrangement whereby a second armature winding of less ampere turns may be substituted for the first;

Fig. 6 shows an arrangement whereby the number of cells of batteries in the motor circuit may be increased; and

Fig. 7 represents the theoretical speed-output characteristics of a motor arranged in accordance with our invention, the armature resistance being disregarded and the magnetic flux being assumed to increase in constant proportion to the magnetizing ampere-turns.

In Fig. 1, the electric starting motor has its armature 1 connected to the shaft of the internal combustion engine 2 by suitable gearing 3, and is provided with a series field winding 4 and another series field winding 5 of fewer turns. The winding 4 is connected to the contact 6 of a switch, and the winding 5 is connected to the contact 7, the battery 9 being connected on one side to the contact 8 and on the other side to one commutator brush. Upon depressing the switch lever 10, the battery 9 is first connected to the series field winding 4, and then to the series field winding 5, the field of the motor first being magnetized to a normal degree by the winding 4 and then to a lesser degree by the winding 5. According to Fig. 2, the series field windings 4 and 5, which in this case have the same number of turns, are first connected in series by the switch 10 to produce the normal magnetization of the field of the motor, and are then connected in parallel by throwing the switch lever to its upper position to thereby decrease the field magnetization. In Fig. 3, there is a single field winding 4 which is connected to the battery 9 by the switch 10 to produce normal excitation of the motor, and which is connected to the battery in parallel with the shunt 11 when the switch 10 is further depressed to thereby produce a weaker field magnetization. The arrangement shown in Fig. 4 is such that the field winding 4 remains connected to the battery 9 through the switch 10, while the shunt 12 connected across the armature terminals is disconnected by opening the switch 13, the result being to increase the speed of the motor by increasing the armature ampere turns. According to Fig. 5, the armature has two windings 14 and 15, either of which is connected in series with the field winding 4 by the switch 10. The armature winding 14 provides a number of ampere turns suitable for the normal operation of the motor, and

the winding 15 provides a fewer number of ampere turns.

In all the arrangements hereinbefore described, and in suitable combinations thereof, electrical means are provided for appropriately changing the speed-torque characteristic of the motor so that the motor tends to attain a second point of maximum output equal to or greater than the first one attained under normal conditions of operation, and if desired the change may be made in this way more than once during the starting period, or gradually so as to maintain the motor at the maximum output over a considerable period by gradually altering the magneto motive force effective on the magnetic circuit of the motor, as, for instance, by gradually decreasing the number of turns included in the winding 5 of Fig. 1, or by gradually decreasing the resistance of the shunt in Fig. 3 or increasing that of Fig. 4.

According to Fig. 6, the maximum output of the motor is caused to recur one or more times by increasing the number of cells in the battery 9 connected to the motor, the motor speeding up at each increase. Fig. 7 shows theoretically the speed-output curves of a series electric motor with different field excitations or with different armature ampere turns. If the motor is adjusted for curve I, the output would attain its maximum value a and then decrease, the acceleration decreasing at a rapid rate therewith.

Now, by changing the motor to curve II in accordance with one of the foregoing arrangements substantially at the time that the value a of curve I is attained, for instance, by making the change at b , another output c theoretically equal to a is produced by the motor. Similarly, by changing over to the characteristic III at point d , the maximum output again recurs at e . It will also be apparent that the output may theoretically be maintained substantially constant along the line a, e by introducing the gradual change of conditions hereinbefore referred to. In this way, the average horse-power output of the motor during the starting period is materially increased, thereby increasing the average acceleration of the engine to its critical speed, whether the critical speed is at a normal or at an abnormal value.

In practice, and particularly with the series electric motors ordinarily used for starting internal combustion engines, the point of second maximum output is greater than the first and the third greater than the second, the effect being to increase the average acceleration between the normal and abnormal critical speeds, and, therefore, from rest to the abnormal critical speed, above the theoretical values indicated by the curves of Fig. 7.

It will be understood from the foregoing,

that the desirable quick turn obtained by hand in starting a small engine is more closely approached by this method of starting by a motor than has heretofore been possible. By adjusting the normal operation of the motor in such manner that it attains its first maximum output substantially at the normal critical speed of the engine, the speed at which the engine will reliably pick up under the worst likely conditions is reached at higher average acceleration from the first maximum output than could otherwise be attained, even if the abnormal critical speed should be beyond the final point of maximum output. Furthermore, the average acceleration obtained in this way from rest to the first point of maximum output is increased because the speed of the engine is then lower than would be appropriate if the output of the motor continually decreased after this point, as is the case in prior systems. Finally, the average acceleration throughout the entire starting period may be, in accordance with our preferred method of starting, the maximum attainable within the heating limitations of the motor. Not only the time of starting is decreased as a result of the higher average acceleration to the critical speed, whether normal or abnormal, but the energy consumed is less and the size and weight of the entire starting equipment, including the battery, are reduced.

It is to be understood, of course, that in operating in accordance with our method of starting, the operator so times the actuation of the switch or switches that the characteristic of the motor is changed at the proper points. Inasmuch as the entire period is of short duration, the switch or switches may be so designed that a continuous movement of a foot pedal produces the proper sequence of connections and at the time required in order to accord with the method of starting hereinbefore described.

Having thus described our invention, what we claim is:

1. The method of bringing an internal combustion engine up to its critical speed by means of a motor connected thereto, which consists in initiating the starting operation with the motor arranged for developing a predetermined speed-torque characteristic at the engine shaft, and changing the speed-torque characteristic at the engine shaft at substantially the time the engine reaches its normal critical speed.

2. The method of bringing an internal combustion engine up to its critical speed by means of a motor connected thereto, which consists in initiating the starting operation with the motor arranged for a predetermined speed-torque characteristic, and changing the motor to a different speed-torque characteristic at substantially the

time the engine reaches its normal critical speed.

3. The method of bringing an internal combustion engine up to its critical speed by means of an electric motor connected thereto, which consists in connecting a source of current supply to the motor terminals to cause the motor to develop a predetermined speed-torque characteristic, and changing a circuit of the motor to change the motor to a different speed-torque characteristic at substantially the time the engine reaches its normal critical speed.

4. The method of bringing an internal combustion engine up to its critical speed by means of a series electric motor connected thereto, which consists in connecting a source of current supply having a constant voltage to the motor terminals to cause the motor to develop a predetermined speed-torque characteristic, and changing a circuit of the motor to change the motor to a different speed-torque characteristic at substantially the time the engine reaches its normal critical speed.

5. The method of bringing an internal combustion engine up to its critical speed by means of an electric motor connected thereto, which consists in connecting a source of current supply to the motor terminals to cause the motor to develop a predetermined speed-torque characteristic, and changing the motor to a different speed-torque characteristic at substantially the time the engine reaches its normal critical speed by altering the magnetomotive force of one of the elements of the motor.

6. The method of bringing an internal combustion engine up to its critical speed by means

of an electric motor connected thereto, which consists in connecting a source of current supply to the motor terminals to cause the motor to develop a predetermined speed torque characteristic, and changing the motor to a different speed-torque characteristic at substantially the time the engine reaches its normal critical speed by decreasing the field ampere-turns of the motor.

7. The method of bringing an internal combustion engine up to its critical speed by means of an electric motor connected thereto, which consists in adapting the motor to reach its maximum output at substantially the time the engine reaches its normal critical speed, and changing the speed-torque characteristic developed by the motor at the engine shaft during the starting period to cause the motor to reach another point of maximum output at a higher speed.

8. The method of increasing the average acceleration in bringing an internal combustion engine up to its critical speed by means of an electric motor connected thereto, which consists in connecting the source of current supply to the motor terminals, adapting the motor to reach its maximum output at substantially the time the engine reaches its normal critical speed, and decreasing the field ampere-turns of the motor at substantially that time.

In testimony whereof we affix our signatures, in presence of two witnesses.
